UNITED STATES PATENT OFFICE.

PHILIP HUSTON HAMMOND, OF THE UNITED STATES NAVY.

SEXTANT.

1,191,073.

Specification of Letters Patent. Patented July 11, 1916.

Application filed June 20, 1913. Serial No. 774,786.

(DEDICATED TO THE PUBLIC.)

To all whom it may concern:

Be it known that I, PHILIP HUSTON HAMMOND, of the United States Navy, a citizen of the United States, residing at Annapolis, in the county of Anne Arundel and State of Maryland, have invented or discovered certain new and useful Improvements in Sextants, of which the following is a specification, reference being had 10 therein to the accompanying drawings.

This application is made under the provisions of the act of March 3, 1883, Ch. 143: 22 Stat. L. 625, and it is understood that the invention described herein, if patented, 15 may be used by the Government, or any of its officers or employees in the prosecution of work for the Government, or by any other person in the United States, without the payment to me of any royalty thereon.

20 This invention relates to sextants and has for its general object to provide means whereby the graduated limb and vernier may be conveniently illuminated in order to facilitate the taking of nautical and other 25 observations in the dark.

The more particular objects of the invention, together with means whereby the same may be carried into effect, will best be understood from the following description of 30 certain forms or embodiments thereof illustrated in the accompanying drawings. It will be understood, however, that the constructions described and shown have been chosen for illustrative purposes merely and 35 that the invention may be embodied in other forms without departing from the spirit and scope thereof.

In said drawings—Figure 1 is a plan view of a sextant having my improvements 40 applied thereto. Fig. 2 is a front view of the same. Fig. 3 is an enlarged vertical, sectional view taken on a plane passing through the graduated limb and vernier arm. Fig. 4 is a plan view of a portion 45 of the graduated limb and vernier arm showing a modified form of illuminating device. Fig. 5 is a side view, partly in section, of the parts shown in Fig. 4. Fig. 6 is a detail, sectional view taken substantially on the line 3—3, Fig. 5. Fig. 7 is a detail, perspective view of the contact members associated with the lamp shown in Fig. 5.

Referring first to Figs. 1 to 3, the sextant 55 proper may be of any usual or well known construction comprising essentially a frame

12, provided with a handle 13 and carrying a graduated arc or limb 14 and a horizon glass 15, a telescope 16 rigidly mounted on frame 12, and a vernier or indicator arm 17, 60 pivoted to the frame and carrying adjacent its pivot the usual index glass 18 and adjacent its outer end the usual indicator or vernier 19.

In accordance with the present invention 65 the usual reading glass 20 is carried by a supporting arm 21 pivoted for movement at 22 on an arm 23 which in turn is pivoted for movement on the upper or outer end of a post 24 projecting from the vernier arm 17. 70 Adjacent the usual vernier opening 25 in the arm 17, and supported on said arm, as by a bracket 26, is a translucent screen 27 of any suitable material, preferably ground glass. Supported by the arm 21 immedi- 75 ately in the rear of the screen 27 is an incandescent electric lamp 28, behind which is arranged a preferably concave mirror or reflector 29 carried by an arm 30 secured to the arm 21. For supplying current to the lamp 80 28 there are provided wires or conductors 31 connected with said lamp in any suitable manner, extending rearwardly along the vernier arm 17, to which they are preferably secured as by clips 32, and entering the han- 85 dle 13, which is formed hollow to constitute a housing for a dry battery of any usual type with which said conductors 31 are suitably connected. For controlling the current to the lamp 28 there is provided a rod or 90 button 33 adapted to coöperate with any suitable or well known form of switch or contact member within the handle 13, said rod or button being carried by a flat spring 95 34, secured to the end of said handle and adapted normally to hold the rod or button 33 in a position to keep open the circuit to the lamp, said rod or button being capable of being pushed inwardly against the resistance of said spring for the purpose of closing 100 said circuit and causing said lamp to be lighted.

In use the handle 13 is grasped in the hand of the observer and the observation taken in the usual manner, as will be familiar to those skilled in the art, after which, in order to facilitate reading the result of said observation, the rod or button 33 may be pushed inwardly by the thumb or finger of the hand grasping the handle 13, whereupon the lamp 110 28 will be lighted, as above explained. The light from said lamp, reflected and concen-

trated by the reflector 29, is directed upon the translucent screen 27, which causes the same to be diffused evenly over the vernier 19, and the portion of the limb 14 appearing through the vernier opening 25, illuminating these parts and permitting the reading to be readily observed in the dark.

In the modification shown in Figs. 4 to 7, the construction of the sextant may be substantially as shown in Figs. 1 to 3, or otherwise, in accordance with any usual type. As in Figs. 1 to 3, 14 denotes the graduated limb or arc, 17 the vernier or indicator arm, 19 the vernier, and 25 the vernier opening in the arm 17 adjacent vernier 19 through which the graduations on the limb 14 may be observed. As in the form of the invention first described, a translucent screen 270 is arranged upon the vernier arm 17 adjacent the vernier opening 25, and a reading glass 200 is carried by the outer end of an arm 210 pivoted to an arm 230 which in turn is pivoted to a post 240 projecting from the vernier arm 17. In this form of the invention, however, the lamp 280 and reflector 290 are carried by a slide 35 mounted on the arm 210 and adapted to move longitudinally thereon and to be held frictionally in any desired position. Also in this form of the invention the current to the lamp 280 is controlled by means of a switch comprising a pin 37 projecting from the lamp socket 38 in the slide 35 and an angular spring contact member 39 secured to said slide, as by means of screws 40 passing through a cap 41 and through openings in one arm of said contact member 39, and entering said slide 35. The conductors 310 are connected respectively with the lamp socket 38 and with the contact member 39. When it is desired to light the lamp 280 for the purpose of illuminating and reading the scale and vernier, the contact member 39 may be pressed inwardly against

its own resilience into contact with the end of pin 37, thereby closing the circuit to the 45 lamp. When using the instrument in the day time, or when for any other reason the use of the lamp is not desired, the slide 35 may be moved inwardly on the arm 210 and out of the way.

Having thus fully described my invention, I claim as new and desire to secure by Letters Patent:—

1. The combination with a mathematical instrument provided with a graduated scale 55 and an indicator arm adjustable relatively to the scale, the said instrument having a handhold portion by which it is grasped and held in position for use, of means for illuminating the scale comprising an electric 60 lamp carried by and movable with the indicator arm, a battery arranged within the said handhold portion of the instrument, circuit wires leading from the battery to the lamp, and a circuit controlling switch adj- 65 cent to the battery.

2. The combination with a mathematical instrument provided with a graduated arc, an indicator arm and a vernier adjustable relatively to the arc, the said instrument 70 having a portion shaped as a handhold for grasping and supporting it in position for use, of means for illuminating the arc comprising an electric lamp carried by and movable with the indicator arm, light reflecting 75 and diffusing members associated with the lamp, a battery housed within the said handhold portion of the instrument and in circuit with the lamp, and a lamp controlling switch adjacent to the battery.

In testimony whereof I affix my signature in the presence of two witnesses.

PHILIP HUSTON HAMMOND.
